CASTRATOR

Filed Sept. 5, 1939

UNITED STATES PATENT OFFICE

2,235,923

CASTRATOR

Bennett B. Gardener, Lake Creek, Oreg.

Application September 5, 1939, Serial No. 293,479

1 Claim. (Cl. 128—306)

This invention relates to castrators for operating upon calves, bulls and horses, and has for an object to provide a tool of this character which will be easy to handle, which will be so constructed that the operator's fingers or hands cannot become pinched by any of the working parts, and which will have novel resilient jaws, the ends of which terminate in working faces disposed obliquely to the longitudinal axis of the tool and offset to one side of the longitudinal axis so that when the jaws are closed the faces will have sliding action relatively to each other to sever the testicle cord and push the severed ends of the cord away from each other, without cutting or injuring the scrotum.

A further object is to provide a device of this character which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming a part of this specification:

Figure 1 is a side elevation of a castrator constructed in accordance with the invention and showing with the jaws closed.

Figure 2 is a side elevation of the device shown with the jaws open.

Figure 3 is an end elevation of the device.

Figure 4 is a top plan view of the device.

Figure 5 is a cross sectional view taken on the line 5—5 of Figure 1.

Figure 6 is a top plan view of a modified form of jaws.

Figure 7 is a fragmentary side elevation of the jaws shown in Figure 6.

Figure 8 is a fragmentary side elevation of the jaws shown in Figure 1, and showing the same in operative position to sever the cord without injury to the scrotum.

Referring now to the drawing in which like characters of reference designate similar parts in the various views, 10 designates a pair of substantial straight levers pivoted together at the lower ends through the medium of a pivot pin 11 passed through hinge ears 12 formed in the curved lower end 13 of one of the levers, and in 55 the straight lower end 14 of the other lever. A

leaf spring 15 is disposed between both levers, one end of the spring being engaged in a recess 16 in one of the levers. The spring bears against both levers and normally holds the levers open.

The levers terminate in the arcuate jaws 17 which when closed define a substantially oval opening between them to allow room for the operator's fingers when operating the tool without danger of the fingers being pinched. The jaws are formed of resilient material and terminate in 10 working faces 18 which are disposed obliquely to the longitudinal axis of the tool and are offset to one side of the longitudinal axis of the tool, as best shown in Figure 1. By virtue of the jaws being formed of resilient material, and by virtue 15 of the arrangement of the working faces, when the jaws are closed the working faces slide relatively to each other on the cord, to sever the cord and push the severed ends apart, without injury 20 to the scrotum.

A pair of side plates 19 are secured in any preferred manner to the edges of one of the levers 10 and slidably receive the other lever. Both side plates have extensions 20 on one side, best 25 shown in Figures 1 and 2.

A roller 21 is mounted on a pivot pin 8 carried by the head of an operating lever 22, which is pivoted between the extensions 20 through the medium of a pivot pin 8. The head of the operating lever 22 is cut away at one corner as shown at 7 to receive the roller. The roller is adapted to bear against the adjacent lever 10 near the base of the respective jaw 17, and when the operating lever 22 is rocked to the open position, shown in Figure 2, the roller 22 will be 30 swung in an arc about the pivot pin 8 downwardly to a point underneath the pivot pin to permit the spring 15 to open the jaws. When the operating lever is closed as shown in Figure 1, the roller 21 swings in an arc around the pivot 35 pin 8 and cams the adjacent lever 10 toward the opposite lever to close the jaws, thus allowing 40 all levers to be locked together.

The side plates 19 and the extensions 20 thereof co-act in forming a housing which houses all 45 the working parts of the tool. Consequently the operator's fingers cannot be caught and pinched by the working parts of the tool while at the same time the housing forms a guide to direct the levers 10 and 22 accurately during their movement to open and to close the jaws.

A modified form of jaw is shown in Figures 6 and 7. In this form of the invention the jaws 23 provided with working ends 24 and the working 50 end of one of the jaws is provided on the sides 55

with flanges 25 which overlap the sides of the other jaw and assist in applying the tool to the parts to be operated upon. The working faces 26 of the jaws in this form of the invention are also inclined obliquely with respect to the longitudinal axis of the tool and are offset to one side of the longitudinal axis.

In operation, as best shown in Figure 8, the jaws 10 are closed upon the scrotum 27 and upon 10 the cord 28 to be severed. By firmly closing the operating lever 22 while both the levers 10 and the operating lever 22 are held in the grip of one hand of the operator, the obliquely disposed working faces 18 of the jaws 17 will slide relatively 15 to each other, both of the jaws bowing to permit this sliding movement, so that the cord 28 is first crushed, then severed and finally the severed ends pushed away from each other while the skin of the scrotum is held between the working faces of 20 the tool without injury.

From the above description it will be seen that the tool will be easy to handle, will have the working parts housed to prevent pinching of the

operator's fingers at any time, which will form a substantial oval opening within the enclosure of the arcuate jaws to receive the fingers of the free hand while manipulating the parts to be operated upon without danger of pinching the fingers and will quickly sever the cord and separate the severed ends without injury to the scrotum. 5

What is claimed is:

A tool of the class described comprising, levers, means pivotally connecting the levers together at 10 one end, a spring between the levers normally holding the levers spread apart, means for moving the levers against the tension of the spring toward each other, and resilient arcuate jaws on the ends of the levers terminating in flat working 15 faces disposed obliquely to the path of the movement of the jaws, said working faces being offset from the central longitudinal axis of the tool, both resilient jaws co-acting in yielding relatively to each other to permit the working 20 faces sliding one upon the other when said means is moved to operative position.

BENNETT B. GARDENER.
